UNITED STATES PATENT OFFICE.

ELOV F. MAAS, OF AKRON, OHIO, ASSIGNOR TO THE GOODYEAR TIRE & RUBBER COMPANY, OF AKRON, OHIO, A CORPORATION OF OHIO.

CONTROL DEVICE.

Application filed October 29, 1925. Serial No. 65,629.

My invention relates to machines that are employed in processing flexible elongate materials, such, for example, as chafing strips or plies for pneumatic tires and it has 5 particular relation to those processes wherein several operations are effected by different machines which operate simultaneously but which are not synchronized.

One object of my invention is to provide 10 a device by means of which any irregularities of consumption may be met or overcome without human supervision.

Another object of my invention is to provide a control device which will obviate the 15 necessity of certain machine operators.

In many industries, such for example as the rubber industry, flexible elongate materials are processed continuously. Oftentimes during the course of manufacture the article 20 being treated passes from one machine to another without intermission. In any continuous process which is so designed, however, difficulties arise when one of the several operations is temporarily delayed, since at 25 such time it is necessary that the activities of the other machines be suspended.

Heretofore, this type of control has been handled by the operators of the several machines. But an additional burden placed 30 upon the operator was that of equalizing the rate of supply on the one hand with that of consumption on the other, this being necessary in order to avoid oversupplying or delays.

According to my invention, I have provided automatically controlled means for starting and stopping jointly operated machines, as well as means for controlling the 35 relative rates at which they should operate.

A better understanding of the invention may be had by referring to the drawings, wherein;

Fig. 1 is a front elevational view of a device embodying the principles of my invention;

Fig. 2 is a side elevational view of the device illustrated in Fig. 1, together with rolls of an unwinding device which illustrate the relation of the machine to a particular process; and

Fig. 3 is also a side elevational view of a machine which embodies certain modifications of the invention;

Fig. 4 is a schematic diagram illustrating the electrical connections used for controlling the motor of the unwinding device.

The device consists of a frame having two pairs of vertically disposed angle irons 11 maintained in position by a cross member 12, which is formed integrally with two horizontally projecting members 13 that are 60 connected to the vertical angle irons. A plurality of brackets 14 are rigidly mounted on the frame to support pulleys 15, which conduct two wires or cables 16 that are jointly connected to a weight 17 at one end 65 and respectively to individual journal blocks 18 at their other ends. The blocks are adapted to move in unison but freely in a vertical direction, between the angle irons. Shafts 19 are rotatably mounted in the 70 blocks 18 and support a floating or take-up roll 20. Near the top and bottom of one of the vertically disposed angle irons are mounted stop and start switches 21 and 22. Each switch is operated by a small arm 75 having a roller 23 at its end which is actuated by the journal block as it moves between the angle irons.

A unit such as has been described may be conveniently adapted in a pneumatic tire 80 factory between a bias cutter and an unwinding device. Here the rolls of rubberized fabric have interposed between each convolution a liner material, that is employed to prevent sticking of the unvulcanized 85 composition and must be removed before the product is passed through the bias cutter. Numerals 25 and 26 indicate the last two rolls of an unwinding device employed for this purpose. The roll 25 is connected to a 90 driving motor 34 by a belt 35. The free fabric 24 passes around the rolls and about the floating roll 20 before it enters the bias cutter.

Those familiar with a Spadone bias cutter 95 will realize that the consumption is intermittent in that each cutting operation is performed while the fabric is stationary. After the cut is completed, the fabric moves a distance equivalent to the exact width of ply 100 desired and the severing operation is repeated. It is usual for the motor which operates the bias cutter and that which operates the unwinding device to be connected independently. If, therefore, for 105 any reason the bias cutter is rendered inoperative momentarily a supply of free rubberized fabric will accumulate. For this reason it has been necessary to have one operator watch at least two machines 110

so that in case one is stopped, the others may likewise be brought to rest. By employing the device hereinabove described, the object for maintaining one operator is cared for, inasmuch as the switches are so arranged that when the floating roll engages the lower switch 22, which occurs only when an excess of unwound fabric has accumulated, the operation of the unwinding device is interrupted. When on the other hand the floating roll reaches the upper switch, which obviously occurs only when the supply of free fabric has diminished, the motor of the unwinding device is energized and a supply of fabric is caused to accumulate. In order that all of the weight of the floating roll will not be supported by the fabric, the cable and counter-weight has been provided.

While the embodiment hereinabove described permits of dispensing with the services of one workman, the operation of the unwinding device is not necessarily continuous. In fact, it is expedient that the rate at which the fabric is unwound be slightly greater than the average rate of consumption. By means of a modification of my invention, however, it is possible to control the rates so that the two machines operate substantially continuously. Accordingly, a rack 27 is mounted upon one of the journals and meshes with a gear 28 that has a short pin 29 made integral therewith. The pin is adapted to engage the shoulders of an arcuate cam 30 which is mounted on a shaft 31 of a rotatable type rheostat 32 of any well-known construction. The rheostat is connected in the energizing circuit of the motor which drives the unwinding device.

As best shown by Fig. 4, the electrical connections employed to control the operation of the device include a driving motor 34 that is connected to power lines 36 and 37 and is started and stopped by means of a relay switch 40. The switch is composed of a solenoid or coil 38 provided with a plunger core. A closure element 41 is attached to the lower end of the latter and is adapted to complete or break the electrical circuit between two terminals 42 provided in the line 37. The solenoid is energized by means of electrical current which is controlled by the switches 21 and 22 that are connected in parallel with respect to each other and in series with respect to the solenoid 38 by means of conductors 43 and 44. The upper switch 21 is normally held in open position by a compression spring 47, and the lower switch 22 is normally closed by a similar spring 49. The switches are also connected by means of conductors 45, 51 and 52 to the power main 36.

It has previously been indicated that the switches are operated by contact with the roll 20 as it travels vertically in its guide. The speed of the motor is also regulated by

varying the current in a field winding 53. This function is accomplished by a rheostat 55 that is connected in series to the field winding by means of a conductor 56, and is also connected to the power line 36 by a conductor 60. Assuming that the roller 20 is in the position indicated by the full lines in Fig. 4, the switch 22 is closed and current will, therefore, flow through the solenoid 38, thereby closing the relay switch 40 and operating the motor 34.

As the roller 20 descends the rack bar 27 actuates the rheostat 55 and gradually decreases the resistance imposed in the field winding of the motor, thus allowing more current to flow therethrough and gradually reducing the speed of the latter. In case the roller 20 descends to its lowermost position, it will engage the switch arm 22 and open the circuit 51-44 and thereby deenergize the solenoid to permit the closure element 41 to descend and thus break the circuit to the motor.

As the loop of fabric is diminished the roll 20 rises until it engages the arm 21, thereby closing the circuit between the conductors 45 and 43, and again energizing the solenoid 38 and causing the motor to operate. The fabric will then be fed from the unwinding device.

It will be apparent that the resistance of the circuit will be varied according to the position of the floating roll. It will also be apparent that the length of the rack is equivalent to substantially one and a half revolutions of the gear. Thus, if the floating roll starts moving downwardly from its highest point, at which the motor rotates most rapidly, the resistance will not be varied until the gear has traveled one half of a revolution, after which it will be increased with the continued downward movement. The rate of operation will then diminish until it is substantially equal to that of the bias cutter. If for any reason the bias cutter is stopped, the roll will move downward, causing the resistance in the circuit to increase gradually until the lower switch stops the operation completely. When the bias cutter is started, the floating roll will move upward until it engages the upper switch, at which time the resistance in the circuit is reduced to a minimum and the rates of supply and consumption are again equalized. By placing the starting switch 21 just above switch 22, the starting operation is more gradual inasmuch as considerable resistance is present in the circuit. With any arrangement of switches it is advantageous to have an emergency stop switch at or near the upper limit of travel of the journal, which will stop the entire system.

The advantage of allowing the floating roll to have a margin of play will be apparent by bearing in mind that the rate of

consumption of the bias cutter is distinctly intermittent. During the course of normal operation and at a time when the rates are equalized, the floating roll moves up and down continuously between narrow limits. If play were not provided, the resistance would be varied continuously, resulting in unnecessary fluctuations in current strength and rate of speed of the motor which drives the unwinding device. By employing the means embodying the principles just described, considerable tolerance has been provided wherein the rate of speed remains unchanged.

15 It is not uncommon during the course of operation to have one edge of the fabric which passes around the floating roll relatively loose, as compared to the other. Under these conditions, the roll serves an 20 additional purpose in that it tends to correct these irregularities. It is to be noted, however, that unless the counter-weight 17 has a weight which is greater than one-half the accumulative weight of the roll together with 25 the journal blocks or cross-heads 18, the operation of the device may not be satisfactory. This will be more easily understood by analyzing the conditions which probably exist.

30 When one edge of the fabric is tighter than the other, the roll will be supported by the tighter edge. Under these conditions when the roll is caused to move upwardly, for example, the cross-head which is adjacent 35 to the loose edge must be actuated by the counter-weight, in order that the floating roll may maintain its horizontal position. The remedy is simple in that the opposing counter-weight need be designed to carry 40 slightly more than one-half the weight of the floating roll.

While my invention finds particular application in connection with bias cutters, obviously, a device constructed according to 45 the principles thereof may be used wherever material is processed continuously by machines which are not synchronized or operated by a single control. Its application may be extended to the handling of the calendered or uncalendered fabric during skim coating operations and the like, where regulation is desired. It is to be noted that a 50 variable rheostat of any construction other than one which is rotatably operated may be employed inasmuch as any similar device having spaced engaging means which are actuated by a movement of a floating roll are equally serviceable. Moreover, although 55 I have described a machine embodying the principles of my invention together with a single modification, it will be apparent to those skilled in the art that it is not limited 60 to the construction described, but may be subjected to many variations without departing therefrom, and I desire, therefore, that

only such limitations shall be imposed as are consistent with prior art and the appended claims.

What I claim is:

1. A fabric supply control device, comprising a frame having pulleys mounted thereon, a take up roller provided with journal members mounted for vertical sliding movement in the frame, the take up roller being adapted to rest in a loop in the fabric, individual supporting cables attached to the respective journal members, the cables being trained over the pulleys, a counter-weight common to the cables and being of substantially less mass than the roller and journal means, and means actuated by movement of the take-up roller for controlling the supply of fabric.

2. A fabric supply control device, comprising a frame having pulleys mounted thereon, 85 a take-up roller provided with journal members mounted for vertical sliding movement in the frame, the take-up roller being adapted to rest in a loop in the fabric, individual supporting cables attached to the respective journal members, the cables being trained over the pulleys, a counter-weight common to the cables and being of substantially less weight than the roller and journal means, and means actuated by the movement of 90 the take-up roller for controlling the rate at which the fabric is supplied, said means including electrical switches, and having operating devices placed in the path of the 95 slidable journal members.

3. A fabric supply control device, comprising a frame having pulleys mounted thereon, a take-up roller provided with journal members mounted for vertical sliding movement in the frame, the take-up 100 roller being adapted to rest in a loop in the fabric, individual supporting cables attached to the respective journal members, the cables being trained over the pulleys, a counter-weight common to the cables and being of substantially less mass than the roller and journal means, means actuated by movement of the take-up roller for controlling the rate at which the fabric is supplied, said 105 means including a rheostat, and means associated with the take-up roller, whereby vertical movement of the latter operates the 110 rheostat.

4. A fabric supply control device, comprising a frame having pulleys mounted 115 thereon, a take-up roller provided with journal members mounted for vertical sliding movement in the frame, the take-up roller being adapted to rest in a loop in the fabric, individual supporting cables attached to the 120 respective journal members, the cables being trained over the pulleys and attached to a counter-weight common to the cables and being of substantially less mass than the 125 roller and journal means, means actuated by 130

movement of the take-up roller for controlling the rate at which fabric is supplied, said means including electrical contact members disposed in the path of movement of the 5 take-up roller on opposite sides thereof and operated by contact with the latter, and additional means associated with the take-up roller whereby said rate is gradually varied as the take-up roller moves in its vertical 10 path.

5. A fabric supply control device comprising a frame, a vertically movable roller

mounted in the frame and adapted to rest in a loop of fabric and to be moved vertically in the frame thereby, upper and lower 15 electrical switches mounted on the frame and having arms projecting into the path of the roller so as to be operated thereby, the upper switch arm being adapted to start the motor of an unwinding device and the lower switch 20 arm being adapted to stop said motor.

In witness whereof, I have hereunto signed my name.

ELOV F. MAAS.
